Primary Examiner — Barbara Fox*Assistant Examiner* — Aram Kwon(74) *Attorney, Agent, or Firm* — Locke Lord LLP; Tim Tingkang Xia, Esq.(57) **CLAIM**

The ornamental design for a “portable electronic device”, as shown and described.

DESCRIPTION

FIG. 1 is a top, front and left side perspective view of a portable electronic device showing my new design;
FIG. 2 is a bottom, front and left side perspective view thereof;

FIG. 3 is a bottom, front and right side perspective view thereof;

FIG. 4 is a bottom, rear and left side perspective view thereof;

FIG. 5 is a bottom, rear and right side perspective view thereof;

FIG. 6 is a front view thereof;

FIG. 7 is a rear view thereof;

FIG. 8 is a left side view thereof;

FIG. 9 is a right side view thereof;

FIG. 10 is a top view thereof; and,

FIG. 11 is a bottom view thereof.

The dashed broken lines depict portions of the portable electronic device that form no part of the claimed design.

1 Claim, 11 Drawing Sheets(56)
